LIGHTWEIGHT RAILWAY CAR

William H. Mussey and Martin P. Bloomberg, Chicago, Ill., assignors to Pullman-Standard Car Manufacturing Company, Chicago, Ill., a corporation of Delaware

Application June 17, 1933, Serial No. 676,265

11 Claims. (Cl. 105—397)

The invention relates generally to metallic railway car construction and more specifically to passenger train vehicles fabricated of aluminum or its alloys.

5 Because of the sharp definition of contour obtainable in members formed by the extrusion process, it becomes practicable to unite a plurality of shaped members formed with interlocking faces and so disposed relatively that the assembled 10 whole will present a structural element of such contour as to render it suitable for connection with associated members of the car framing.

In riveted aluminum structures involving the use of many pieces, the greatest uncertainty 15 exists with respect to the integrity of the joints between them. There is no assurance that the connected members will function in unison since the stresses imposed are usually transmitted from one member to the others by rivets, and in all 20 probability the metal about them will yield and the holes become elongated with ensuing deformation of the connected members due to their low deflection value and the unequal stresses imposed. Therefore, the use of aluminum requires 25 that the arrangement and location of parts be such as properly to transmit the stresses set up, giving due regard to the distribution and interengagement of the mass of the connected parts.

Heretofore, the neutral axis of the girder side 30 was invariably found adjacent the bottom chord because of the practice of using lower chord members having sections relatively greater in area than the stress members forming the top chord of the girder. As a result of that arrangement, 35 the area of the girder plate subjected to compressive stresses above the neutral axis was abnormally large, causing the plate to buckle. The relative thinness of the girder plate rendered the plate inadequate for the purpose of transmitting 40 compression stresses, whereupon the top chord member became overstressed by the additional burden of the load normally distributed by such plate to the bottom chord and buckled under the thrust, causing premature failure of the girder as 45 a supporting unit.

Accordingly, an important object is so to dispose, 50 combine and connect the stress elements of the supporting side structure above and below the windows of the car that the major portion of the area of such structure will be free from deforming stresses, the parts comprising the principal longitudinal elements thereof being so connected that the several parts will function as a unit regardless of the magnitude or direction of the stresses 55 imposed.

A particular object of the invention is to provide a car of maximum strength and capacity and of minimum weight, utilizing extruded stress members of advantageous contour and proportion substantially to reduce the number of parts required for its fabrication, and to adapt such members to the contours of associated engaging members of the car framing to reduce the number of joints in the assembly.

A further object is so to dispose and proportion 10 the extruded longitudinal stress members forming the compression chords of the upper and lower girders respectively above and below the window openings that neutral axes of said girders will be placed relatively high with respect to their lower 15 chords constituting the drip mold above the window openings and the car side sills therebelow.

A still further object is to increase the effective 20 top chord area and correspondingly reduce the section of the bottom chord so that the girder 25 plate portion below the neutral axis thus raised will be increased and the area above the neutral axis subjected to compression will be reduced to a minimum to permit the relatively thin girder plate to be utilized for the distribution of stresses 30 and to prevent buckling thereof.

An important object is so to correlate and dispose the several member assemblies entering into 35 the roof framing, side structure and underframe that the respective car sections may be fabricated 40 in the shop and the completed assemblies connected at the erection location.

The invention further contemplates the effective streamlining of the exterior contour of the 45 car body whereby wind resistance to car movement, in the direction indicated by the arrow, will be minimized.

The foregoing and other objects are attained by the construction illustrated in the accompanying 50 drawings, in which

Figure 1 is a side elevational view of one embodiment of the invention;

Figure 14 is a vertical sectional view on line 14—14 of Figure 6 showing bolster side and center bearing arrangement;

30 Figure 15 shows another form of interlocking assembly for the belt rail; and

Figure 16 shows a tongue and groove connection between side plates.

In the drawings, 10 represents a car the embodiment of which in Figures 1, 2 and 3, is shown 35 with its front or vestibule end conforming to a relatively long arc having the plane faces 11 and 12 at an angle to each other and its opposite or rear end shaped with its side walls 13 approaching each other and their ends joined by a door frame 40 14 curved to merge with the side wall ends whereby the end of the car in plan would assume a parabola in contour. From the vestibule 15 at the front end of the car, the side walls 13 extend in flat planes up to and including that portion 45 of the wall area over the end side posts 16, the wall portion extending around the end of the car from the post 16 on one side to a similar post 16 on the opposite side having a general parabolic configuration.

50 Above the belt rail 17, the wall between the side end posts 16 curves upwardly and inwardly in both vertical and horizontal intersecting parabolas incorporating a letter board portion 18 extending between the posts 16 to the roof and secured to the side plates 19. Below the belt rail 17, the side walls are bent horizontally only to conform to the parabolic configuration of the end but in vertical planes, as best shown in Figures 1 and 3.

60 However, between the vestibule 15 and end side posts 16, the side walls 13 extend from side sills 21 to side plates 19 in vertical planes merging with the curved end wall at the end side posts 16 from which points only the walls begin to assume the parabolic configuration at the rear end of the car. The purpose of thus shaping the car body with receding rear wall portions is to provide a slip-stream surface to minimize the suction effect of the vacuum created by the passage of the relatively large bulk of the car through the air whereby the air displaced may wipe such receding rear wall faces without eddying and therefore substantially reducing air resistance, as will be obvious.

75 The letter board plates 18, upper chord side

plate members 22, supplemental side plate members 23 forming also part of the roof assembly, the roof stress plates 24, and the bottom chord drip molding 25, together constitute the upper girder formation. The lower girders comprise the 5 wall plates 26, upper chord belt rail members consisting of the outer and inner longitudinals 27 and 28, respectively, intermediate sill portions 29, post filler members 30 and 31, and bottom chord longitudinals 32. As best shown in Figures 10 3 and 4, the upper and lower girders are connected by narrow posts 33 and relatively wide posts 34, preferably of extruded metal, extending continuously from side sills 21 to side plates 19 and framed into and intersecting the intermediate belt rail 17, the posts forming thrust members in the lower girder upper chord assemblies.

For the purpose of unifying the members of the belt rail assembly, including the posts, the outer rails 27 and inner rails 28 are made to interlock 20 with protruding shoulders 35 and 36 on outer and inner faces of intermediate sill members 29 which at their ends abut squarely against contiguous side walls 37 and 38 of respectively adjacent posts 33 and 34, the continuity of such intermediate 25 members being established by the post fillers 30 and 31 and the metal of post walls 37 and 38, and, if necessary, by filler inserts 50 inserted between them, both inner and outer rails being riveted to the posts, members 29 and fillers 31 to 30 insure complete unity of function between assembly members.

The relatively wide posts 34 have their outer webs formed of upper and lower girder web plate portions 18 and 26 and an intermediate connecting plate 39 extending between the lower edge of the upper girder and the belt rail 17 to complete the unification of the side structure members whereby the full car side will be maintained at a level substantially above the normal deflection values established for the several members entering into the wall structure.

The narrow posts 33 have their web portions 40 forming part of the outer wall sheathing between the upper and lower girders, but are overlapped by and secured to girder plates 18 and 26 at levels above and below the windows substantially to shorten the post column and minimize the bending moment thereof. The posts 33 and 34 on their inner sides are concealed by the usual lining sheets 41 forming no part of the girder structures for stress transmitting purposes. The customary insulation (not shown) of any approved type, may be installed within the spaces between the posts and girder plates and inner 55 lining sheets.

In the spaces between the posts, the plates 44 are secured to the outer faces of the posts in the plane of intermediate connecting plates 39 and have inwardly projecting flanged portions 45 to 60 provide window headers at the window openings, both header and intermediate plates being secured to the upper girder by rivets 46. In the embodiment shown in Figure 4, the extruded metal window sashes 47 are preferably arranged 65 flush with the car side and secured to headers 45, window sills 29, and adjacent posts 33 and 34 by screws 48 whereby the windows 49 are held normally closed in cars equipped with mechanical systems of ventilation for supplying conditioned air to the passengers.

In Figure 5, a double window is shown with outer sash 147 and inner sash 148 slideable in guides 149 secured to the framing posts. The window headers 144 are fitted preferably with 75

wood lintels 145 against which the weatherstrip 146 on outer sash upper rail engages when in closed position, the lintels being supported upon the inwardly extending flanges of the headers.

5 The roof structure is arched between the side plates 23 and secured as a unit to underlying channel-shaped side plates 22 by rivets 51 or otherwise to prevent displacement thereof and insure further cooperation with the side wall 10 structure. The side plates 23 are also preferably channel-shaped with a pair of upstanding outer and inner flanges 52 and 53 with the connecting webs 54 projected outwardly beyond flange 52 and flanged downwardly at 55 to provide a watershed 15 spaced outwardly from the outer flange 56 of the side plate channel 22 beneath and a securing means for the curved roof plates 24 connected thereto by rivets 57. The roof plates 24 are rigid and extend upwardly from the side plate 20 flanges 55 and inwardly for connection to intermediate and relatively light roof sheets 58.

25 The roof plates and sheets are reinforced by carlines 59 extending transversely of the car and supported at their ends upon side plates 23 and held from displacement by the upstanding flanges 52 and 53 to which and the web 54 they are secured by rivets 60 as best shown in Figure 4. The rigid roof plates 24 and the relatively light intermediate roof sheets 58 are preferably 30 joined by riveting as indicated at 61 or by welding, and are further braced and secured at side plate flanges 52 having thickened marginal portions 62 to which the roof plates are connected by rivets 60, the enlarged edges conforming to 35 the curvature of and providing additional bearing area for the plates.

40 The rigid roof plates 24, thus held by a double row of rivets at their lower margins and braced laterally by carlines at spaced intervals and by 45 virtue of their contour, provide in effect beams at the roof line to supplement that afforded by the side wall structure below, whereby the neutral axis X—X of the upper girder is raised to a point adjacent the side plate assembly by increasing 50 the mass of material comprised in the assembly with respect to the remaining area of the girder below the neutral axis. Such distribution of 55 metal assures the placement of the greater part of the girder plate 18 in tension with its lower chord 25 with the result that the relatively thin girder plate is held relatively taut and free from buckling, since the forces of compression will be confined to the relatively small area above the neutral axis and adjacent the top chord assembly.

60 Such distribution of the metal in the girder formation eliminates the difficulty heretofore encountered in securing sufficient stability of structure in aluminum cars because of the relatively low modulus of elasticity of the metal and correspondingly great deflection in the completed car with consequent buckling of the girder plates and overstressing of other and associated parts of the car.

65 Because of the unitary character of the extruded longitudinal stress members of the side plates, the joining together of the several separate members heretofore making up such assembly is avoided and the members shaped to 70 conform to associated parts, as will be evident from an inspection of the side plate member 23 having an outer flange 52 in addition to the inner flange 53 whereby the ends of carlines 59 are nested between such flanges as in a pocket, the 75 outer flange also providing a bearing and secur-

ing means for the curved roof stress plate 24 in planes inwardly of the depending eaves flange 55 so that the assembly would function as a column in buffing.

It will be noted that in one embodiment the 5 upper girder plates 18 are riveted along their upper edges to inner faces of side plate outer flanges 56 and that the eaves flanges 55 spaced outwardly therefrom to provide a watershed are integral with the roof side plate 23 and the roof 10 plates 24 attached to and removable with the roof assembly. In the modified form illustrated in Figure 5, the rigid roof plate 24 is secured to the lower side plate section 122 of the side wall assembly by rivets 157 thru the downwardly extending outer flange portion 155 of the plate. 15

The flange 155 is offset inwardly at 156 and its depending marginal portion 159 secured by rivets 160 to the outer face of upper girder plate 18. The offset flange, by virtue of its shape, provides the necessary watershed at the eaves of the roof and with the web 161 of the side plate channel reinforces the roof plate 24 both laterally and vertically of the car. In the modified embodiment, the side plate 123 for the roof assembly is also channel-shaped with its inner and outer flanges 152 and 153 upstanding to provide a pocket for the ends of carlines 59 in the manner indicated in Figure 4, the outer flange having a thickened marginal portion 162 conforming to curvature of the rigid roof plate 24 bearing against it as in the case of the first embodiment, with rivets 163 securing the roof plate 24 to the flange 153 and rivets 164 of other devices connecting the web 165 of side plate 123 30 with underlying web 161 of side plate 122. 35

As in the case of the side plate members of the first embodiment, the members 122 and 123 are preferably of extruded aluminum and each formed of integral sections of a contour adapted 40 for ready assembly with associated framing members. The inner flanges 166 depending from web 161 may lie flush with adjacent inner flange 152 of the overlying side plate member or stepped inwardly thereof as in the first embodiment depending on extent of eaves overhang desired and width of side posts. 45

The side frame assembly 13 is supported upon side sills 21 of the underframe shown in Figure 6. The sills are of extruded aluminum of general Z-formation and in Figure 4 are shaped to provide a web portion 68, inwardly extending top and bottom flanges 69 and 70 and a relatively wide outwardly projecting bottom flange 71 upon which the bottom chord 32 of the side wall assembly is supported. Upon upper flanges 69, the usual subfloor sheets 72 are provided for supporting the customary floor insulation (not shown) and secured upon the sill flanges by angular stringers having their vertical flanges 73 50 attached to flanges 43 of the framing posts and their horizontal flanges 74 overlying subfloor sheets and secured to sill flanges 69. Upon stringer flanges 74 is laid the usual nailing and spacing stringers 75 for supporting the car floor 55 65 76. It will be noted that the vertical flanges 73 project above the level of the floor 76 at the side wall and function with the underlying horizontal flanges 74 of the stringers to provide an air and moistureproof seal at the floor line. 70

Like the side sill of the first embodiment, the modification illustrates a sill of extruded aluminum and of general Z-formation except that the inwardly extending floor supporting flanges 169 form an integral part of a separately formed 75

floor seal member adapted to interlock with a shouldered thickened edge portion 170 on web 168 of the sill, but the outwardly projecting lower flange 171 for supporting the side wall structure is preferably integral with the web, as shown.

5 The floor seal member is formed to interlock with the sill web to function as part of the side sill and to provide a combined clip attachment for inside finish and a cove molding and support 10 for the floor. For this purpose, the floor supporting flange portion 169 is formed with an up-standing reversely offset flange 173 providing an outer groove 172 for interlocking with and receiving the shouldered thickened edge 170 or 15 tongue portion on the sill web and an inner and relatively higher groove portion 174 to provide a receiving cove for the floor.

The upper edge of the offset flange 173 is formed with a downwardly and inwardly extending 20 hook flange 175 designed to provide an anchorage clip for inside finish sheet 41 at the floor line having a rebent edge portion 176 hooked under the flange as best illustrated in Figure 5. The sill parts are further secured together and 25 to adjacent side framing members by rivets 177 to insure at all times a proper working relation between the interlocking members. The modified adaptation will permit the connecting rivets 177, except those taking the side posts, to be m- 30 achine riveted before assembling with the side wall structure.

In the embodiments of both Figures 4 and 5, the bottom chord angles 32 of the side wall assembly rest upon and are secured to respective 35 outwardly extended sill flanges by rivets 9 hand-driven at the erection location. As in the upper girder construction, the massing of material at the belt rail constituting the top chord member of the lower girder structure has the effect of 40 raising the neutral axis X-X to a point substantially above the median line of the girder, whereby the greater part of the girder plate area with the bottom chords 32 and side sills 21 in tension is freed from compression strains 45 tending to buckle the girder plate, the area of the plate 26 below the outer rails 27 and above the neutral axis being relatively small.

By distributing the mass in the belt rail laterally of the structure as exemplified by the substantial areas of the interlocking inner and outer rail sections 28 and 27 and relatively wide sill member 29 connecting them, the radius of gyration of the belt rail assembly is also substantially increased to effect a lower ratio of slenderness 55 of the column with resultant increase in rigidity of structure and rendering possible the use of aluminum and its alloys in assemblies where the low deflection value inherent in such metal had heretofore been regarded as detrimental to its 60 adoption for such purposes.

The described superstructure is mounted upon the underframe illustrated in Figure 6 and connected as stated to the side sills 21 extending in the present embodiment from the body end 65 sill 77 to the opposite end of the car and conforming to the side wall contour to the buffer end sill 78 at door frame 14 as indicated in Figures 2 and 3. In cars fitted with vestibules 15 at both ends, the sills will extend in a single 70 plane to end sills at both ends of the car. Except for the bending in of the side sills at the curved opposite end of the car beyond the body bolster at that end and the elimination of end sill 77 and vestibule 15, the underframe on op- 75 posite sides of the transverse center of the car

is of similar construction, therefore a portion only of the underframe on one side of the center will be shown and described.

The center sill construction is fashioned somewhat on the order of that covered in Patent No. 5 1,804,428 issued May 12, 1931, to W. H. Mussey, for car underframe construction, but differs materially therefrom in structure presently to be described. As in the prior patent, the top chords 79 and bottom chords 80 of the center sill are 10 channel-shaped with their flanges 81 bent laterally to provide horizontal securing flanges 82, the channels respectively opening upwardly and downwardly.

Between the bolsters the sill chords are spaced 15 apart by crossbearers 83 and struts 84 and between the crossbearers and vestibule 15 by pressed channel draft sill members 85 secured to and extending from the crossbearers 83 at their deepest point and tapering to the body bolsters 86 through 20 which to the vestibule the height of such members remains uniform. The bottom chord between crossbearer 83 and a like crossbearer at the other end of the underframe is straight, and, in the present embodiment, slopes upwardly from 25 said crossbearer to the bolster 86, then straight through the bolster to points intermediate the respective bolsters and end sills 77. The top chords 79, however, extend to points beyond the end sills for connection with inwardly extending 30 buffer housing portion 87 of the buffer end sill casting 78 supported upon the pressed channel draft sill members 85 which extend to the buffer end sill and are secured to it.

Between the draft sills, the buffer cushion 35 housing portion of the buffer casting is inserted with its side walls 88 secured by rivets 89 to webs 90 of the draft sills. Projecting outwardly from the upper edges of the housing side walls are supporting wings 91 overlying the draft sill top 40 flanges 92 and secured thereto by rivets 93, the flange riveting area being depressed below the normal top face of the wings so that the rivet heads will not interfere with the normal placement of the usual sectional platform plate 94 extending between and secured to the step risers 95 by rivets 96 and to the buffer wings by screws 97 to permit removal of the intermediate section of the platform plate for access to the housing 87.

The buffer casting wings 91 extend rearwardly to the end sill 77 and unite back of the housing portion 87 to provide connection webs for the ends of the center sill top chords 79. The webs conform to the contour of the sill chord and provide a major portion 98 secured to the webs 99 of the top chords between the flanges 81 and portions 100 in a higher plane for engagement with and connection to adjacent top chord flanges 82.

As indicated in Figure 6, the pressed draft sills 85 have their upper and lower flanges 92 and 101 secured to and between outwardly extending flanges 82 of respectively adjacent sill chord flanges 81 to form with such chords a box girder sill portion framed into the bolsters and extending to adjacent crossbearers 83 to provide a 65 rugged column having open channel faces upon all of its sides. The bottom channel face is adapted to receive a center bearing plate 119 beneath the web 99 of the bottom chord 80 at the bolsters 86.

The side channel faces receive the strut members 84 and inner ends of bolster diaphragms 103 and floor pans 121, and the upper channel face receives the nested portion 98 of the buffer end sill extensions 91 at the end sill, by virtue of 75

which the connections between such parts and the center sill occur at points closer to the neutral axis of the sill than are the polar limits of the column, insuring thereby a balanced transmission of buffing forces through the transverse members to the car sides. The center sill between the crossbearers 83 is open and the top and bottom chords at that section are tied together by struts 84 and intermediate crossbearers (not shown) 10 since the sill chords at this point are parallel to the lines of impact and require only that they be held in alignment.

The bolsters 86 comprise each the diaphragms 103 placed back to back and extending between the center and side sills, the sills and diaphragms being connected by a top cover plate 104 extending from side to side and bolster to bolster to provide a unitary assembly. The undersides of the bolsters are covered by separate compression plates 105 extending beneath and tying together the sills and diaphragms and fitted at their respective opposite ends with jacking pads 106 secured to the plates and adjacent side sills by rivets 107. The bolsters 86 adjacent their ends are further united and braced by hollow side bearing beams 108 connected to the bolsters by angle clips 109 secured to the webs of diaphragms 103 and side walls 110 of the beams.

The beams are preferably channel-shaped with their side walls flanged outwardly at 111 for connection with the bolster top cover plate 104 to form therewith a box girder construction providing a rigid column for distributing shocks of impact and substantially reinforcing the bolster assembly, the outer flanges of the beams being spaced from adjacent margins of the top cover plate to secure upper flanges 69 of the side sills between them for a more complete integration of the underframe elements in the bolster area. As shown in Figure 14, the side bearing beams 108 are fitted with side bearing shoes 112 recessed on their bearing faces to accommodate a suitable lubricating insert 113 adapted for frictional contact with underlying truck side bearings 114.

The shoes 112 are yieldingly held to the hollow beams 108 by bolts 115 provided with securing nuts 116 and suitable spring washers 117 having bearing upon the nuts inside of the beams and the bolt heads at the shoes so that upon compression of the rubber cushion 118 between the beams and shoes under pressure of the truck side bearings 114 during swaying movements of the car body, the shoes will yield to such movement but the bolts securing them will be held taut and the slack created by the upward thrust of the bolts taken up by the spring washers 117, to prevent the clash of metal parts resulting in cases where no provision is made for cushioning the blows or taking up slack in the securing members.

With the arrangement described, it is possible to maintain, at all times, a cushioned contact between body and truck bolsters at the side bearings with the body center bearing plate 119 in bearing engagement with the supporting truck center bearing plate 120, as best illustrated in Figure 14.

For the purpose of rigidifying the bolster assembly at the center bearing position, a bearing filler block 200 is inserted between the sill chord webs 99 and formed with a tubular pin bearing 201 for a king pin 202, the bearing having an extended lower portion 203 projected through the lower sill web for interlocking engagement with the body center bearing plate 119 nested within the lower chord channel of the center sill

and secured to web 99 and lower portion of the filler by rivets 116, the filler block on its upper side being secured to adjacent top chord web 88 by rivets 117, the top cover plate 104 and both sill webs having openings registering with the tubular bearing 201 for reception of the king pin 202.

In the form illustrated in Figure 14, the body center bearing plate is provided with a filler block and sill reinforcing portion 204 nested within the lower face of the center sill and shaped with a socket portion 205 in its upper face to receive the projected sleeve portion 203 of the king pin bearing 201 on the bolster filler block 200. Beneath the socket 205, the center plate is formed with a tubular portion 206 extending downwardly below the base of the plate to provide a second projection 207 for swiveling engagement with the center bearing plate 120 supported upon the truck bolster 208.

The body center bearing plate 119 is further provided with an annular depending flange portion 209 in concentric relation to the sleeve projection 207 and defining between them a swivel bearing portion 210 for the reception of a complementary upstanding bearing portion 211 on the truck center bearing plate. Between the swivel bearing portions 210 and 211 of the body and truck center plates is interposed a lubricating plate 212 adapted to be held from displacement by the concentric flange 209 and sleeve projection 207 on the body plate.

Thus positioned, the bearing surfaces of the center plates are protected from the elements whereby complete lubrication of these surfaces may be effected and maintained free from dirt and moisture from without. The oil released by the lubricating plate 212 finds its way between the walls of bearing 211 on the truck center plate and contiguous bearing faces on concentric flanges 207 and 209 on the body center plate. The truck center bearing plate 120 has a base plate portion 213 held in recess 214 in the truck bolster 208 and preferably mounted upon a shim plate 215 of wood or the like also within the recess 214 as shown in Figure 14.

The whole assembly, including the truck bolster 208, truck and body center bearing plates 120 and 119 and interposed lubricating plate 212, the bolster filler block 200 and body bolster 86, is held operatively connected by the locking king pin 202 held from rotation within the tubular bearings 201 and 206 by keepers 216 resting upon upper chord 79 of the center sill and engaging one side of the polygonal head 217 on the pin.

The pin projects downwardly into the truck bolster and is provided at its lower end with a threaded portion 218 fitted with a polygonal nut 219 nested in socket 220 on the truck bolster so that as the truck swivels about the king pin the nut will turn with it without disengagement from the pin. The structure at the bolster position is further strengthened against possible distortion of the cover plates 104 above the center sill. The cover plates normally function in tension, but when the car is supported upon jacks at the jacking pads 106 at the ends of the bolsters, the cover plates 104 are placed in compression.

Therefore, to prevent buckling of the cover plates, top and bottom, at the point where they bridge the upper and lower troughs of the center sill, suitable filler blocks 178 are inserted fore and aft of the plates between the plates and webs 99 of the top and bottom chords 79 and 80, as

best shown in Figures 6 and 14, and secured to both plates by the several rivets 179 to insure proper transmission of the stresses thus imposed. At the bolster diaphragm positions, the draft sills 85 and center sill top and bottom chords 79 and 80 are further held in proper spaced relation by bolster filler pans 180 secured to webs 90 of the draft sills and webs 99 of the sill chords. The rivets 181, securing the pans to the top chord web, also connect the respectively adjacent filler blocks 178 to the sill, as indicated in Figure 14.

The struts 84, in the present embodiment, comprise each an open channel intermediate section 182 and open top and bottom connections, all preferably of extruded metal, but the struts as a whole may be unitary pressed pan members as to all of their parts, if desired. The top and bottom connections are similar in form, each provided with spaced flanges 183 projecting from the base portion of the connection and assembled with the intermediate channel sections 182 with their respective flanges between and in overlapping engagement with the channel flanges 186 to which they are secured to complete the strut structure as by rivets 187, the assembled units 84 being secured to adjacent top and bottom sill flanges 82 through the medium of base plate portions 184 of the strut connections. These struts serve also to connect the various floor pans 121 and crossbearers 83 to the center sill by means of rivets 188 taking one or the other of strut channel flanges 186 as indicated in Figure 6.

The end sill 77 comprises, in the present embodiment, a continuous antitelescoping plate portion 221 extending between and secured to the inwardly projecting upper flanges 69 of the side sills, a pair of U-shaped transverse members having base plate portions 222 and front and rear upstanding flanges 223 and 224, respectively, extending from opposite sides of the center sill to the side sills 21. The rear flanges 224 are bent rearwardly along their upper margins to provide attaching and supporting flanges 225 for adjacent edge of the antitelescoping plate 221 which bridges the gap between the flanges 225 across the center sill and connects the U-shaped members to unify the end sill assembly. These members are further reinforced transversely of the car by continuous angular members 226 secured to the upper side of the antitelescoping plate 221 to which and the underlying supporting flanges 225 they are secured by rivets 227, as best shown in Figures 6 and 9.

The U-shaped members are connected to the draft sills 85 by connections 228 or otherwise and supported at their opposite ends upon the inwardly projecting lower flanges 70 of the side sills. The U-shaped members are further stiffened by underlying cover plates 229 secured to base plates 222 of the members and preferably extending from the draft sills 85 to the side sills. These cover plates are of substantial width and formed with downwardly extending flanges 230 at their inner ends for connection to the draft sills and secured to the underside of inwardly and outwardly projecting lower flanges 70 and 71 of the side sills by rivets 231 whereby such plates would function as gussets to preserve the rectangular relation between end sill and draft and side sills although separate gussets at draft and side sill positions would meet the requirements in cases where the intermediate portions

of the end sill members thus connected do not require the reinforcement afforded by the extended cover plates shown.

The continuity of the outer flanges 223 of the end sill U-shaped members is established by angle members 232 extending across the center sill and connecting the respectively adjacent ends of flanges 223 to which they are secured by rivets 233 as indicated in Figure 8, the member 232 serving also to support the inner edge of platform plate 94 between the step risers 95. The antitelescoping end sill plate 221 is further stiffened along its rear margin by flanges 189 extending transversely of the car between center and side sills and between side walls 81 of the center sill top chord 79.

The door posts 234, diagonal braces 235 and intermediate stiffening posts 236 of the end wall framing assembly are all of them framed into the end sill with their respective lower ends between the upstanding front and rear flanges 223 and 224 of the U-shaped members. The door posts 234 are preferably channel shaped with their flanges riveted to end sill flanges 223 and 224. The diagonal braces, however, are of less depth and secured to front flanges 223 of the end sill members, while the intermediate stiffening posts are of less depth than the other posts and secured to the rear flanges 224 of the end sill members, but only the post members 234 and 236 are extended to connect with adjacent carlines 59. The interior wall sheets 237 which are interposed at this point extend downwardly upon opposite sides of the door opening 238 to the floor 76 and to a point above the door opening 35 to define the door lintel 239, the door and intermediate posts being secured to said sheets between floor and carlines, as best shown in Figures 8 and 9.

At the end wall position the side plates 23 support an end plate 240 extending transversely between and connecting the ends of the side plates and adjacent ends of carlines 59 and uniting adjacent ends of the post and brace members of the end framing, as shown in Figures 8 and 9. The end plate 240 is in the form of a channel with its web 241 extending vertically and its upper and lower flanges 242 and 243 outwardly, the lower flange 243 serving as an attaching member for the vestibule ceiling sheets 244 and securing flange 245 for the outer lintel finishing sheets 246.

The end plate channel provides a connection 247 for the inner ends of longitudinal members 248 having their opposite ends secured to vestibule end posts 249, whereby shocks of impact upon said posts or imposed by the action of associated upper buffing mechanism 250 during normal surging movement of connected cars in a train are transmitted to the end plate and by it to the side plates 23. The post members 234 and diagonal braces 235 are also secured at their upper ends to web 241 of the end plate 240 which thus acts to rigidify the whole end framing assembly at the roof line, rivets 251 securing the door posts and connecting the diagonal braces to the end plate and the sheathing sheets 252.

The braces 235 extend from adjacent the door posts at their lower ends to adjacent the side plates at their upper ends so that in the event of collision and collapse of the end framing assembly, possible telescoping of the cars would be prevented by the gathering-in of the side 75

plate longitudinals with their connecting end plates 240 into the path of the invading car to check its progress to the car interior. The gathering-in of the end framing assembly would 5 result only in the event of the complete destruction of antitelescoping vestibule end posts 249 under thrust of the invading car. In the present embodiment, these posts are tubular and entered in pockets 253 in the buffer end sill 78, as best 10 shown in Figures 6 and 8 through 13. In their preferred form, the posts 249 are made up of two complementary channel shaped webs 254 and 255, the one nested within its companion member with their flanges overlapped and secured 15 together, preferably by welding.

The posts are made larger at their base and tapered thence upwardly and secured to the roof end carline 190 as indicated in Figure 9 and are 20 shown with their inner faces 256 inclined with respect to adjacent inner walls 257 of respective 25 pockets 253 to provide a wedge-shaped opening 258 therebetween adapted to receive a locking wedge 259 designed to prevent withdrawal of the posts from their pockets and develop the full 25 strength of the posts to resist thrusts of impact from the invading car at points above the vestibule platform.

To preserve the contour of the posts at their 30 lower ends under impact pressures and provide the maximum resistance to bending at the buffer end sill, the posts are fitted at their lower ends with tubular filler blocks 260 conforming to the 35 contour of the posts and adapted to be entered between the sides thereof after the posts have been positioned on the car with their lower ends inserted in the buffer end sill pockets 253 and 40 before the locking wedges 259 have been driven. To facilitate the assembling of posts and fillers with the buffer end sill, the post pockets 253 at 45 their lower wall peripheries are formed with inwardly projecting ledge portions 261 along three sides of the openings upon which the posts are 50 adapted to be supported. The filler blocks are formed for telescopic engagement with the posts and secured by bolts 262 extending transversely 55 through opposite walls 263 of the filler, webs 254 and 255 of the posts, and webs 264 and 265 of the buffer end sill 78, as best shown in Figures 8, 9, 11 and 12.

It will be noted that the filler blocks 260 extend 55 with their bodies well above the upper level of the buffer end sill to provide substantial reinforcement for the posts against bending and possible shear at the platform. To insure accurate registration of the bolt openings for the securing bolts 262 and prevent upward movement of the filler blocks 260 beyond their assigned positions within 60 the zone of the buffer end sill during the operation of assembling, the blocks are formed with stop flanges 266 extending along their lower wall edges at three of the sides of the block corresponding to the position of the post supporting ledges 261 on the buffer end sill so that such flanges will engage the undersides of the post 65 ledges to permit application of the block supporting bolts. With the filler blocks in position within the posts and secured, they function as backing blocks to preserve the contour of the relatively light posts under pressure of the wedges 70 259 driven in between the inner walls 257 and adjacent inclined faces 256 of the posts.

It will be noted that the wedges 259 have their 75 post-adjacent faces conforming to and engaging the sloping post faces 256 and their opposite faces parallel to and engaging the vertical pocket walls

257 and are held from displacement by welding the upper edges thereof to the posts and/or buffer end sill, as shown at 267, and at their lower edges to the buffer end sill as best indicated at 268 in Figure 12. By virtue of the construction described, the vestibule end posts 249 are held interlocked with the buffer end sill against withdrawal and shear under impact, and because of the use of post filler blocks designed to receive the thrust of the locking wedges 259, the relatively light post sections are held from distortion under the crushing pressures developed at the post bases during car movement.

The vestibule end of the car is covered by wall sheathing side sheets 12 secured to the hollow 15 posts 249 and vestibule corner posts 269, buffer end sill 78 and roof end carline 190, and by intermediate sheets 11 secured to the roof end carlines and upper ends of the hollow posts 249, as shown in Figures 8 and 9. The posts 249 are formed 20 with portions of their upper ends cut away and tapered as at 270 as indicated in Figure 9 to permit the driving of rivets 271 connecting adjacent wall sheets 11 and 12 to the posts at that point, the remaining portions of wall sheets 12 being 25 secured by machine screws 272 tapped into said posts. These sheets are further secured to the posts by vertically disposed angle members 273 30 extending along the inner faces of the sheets and one side of the posts and riveted to both to insure proper stability of the wall structure at the diaphragm position. The diaphragm 8 is secured by the usual attaching angles 274 also screwed to these posts. The car vestibule 15 is closed by the usual side doors 4 opening inwardly against 35 the car end wall and by platform trap doors 5 covering the step 6 and adapted to be raised against the vestibule doors when open. Slidable doors 3 in door frame 14 provide access to or exit from the rear end of the car, as best shown in Figure 2.

The interlocking feature between stress members of extruded aluminum shapes represented in the interengagement between the side sill members illustrated in Figure 5 is further exemplified in its use between the members of the belt rail assembly shown in Figure 15 and between the side plate longitudinals illustrated in Figure 16. The belt rail assembly of the embodiment indicated in Figure 15 comprises the outer rail member 327, the inner rail member 328 and intermediate and relatively wide sill portion 329, all interlocked to provide a longitudinal framing sill element, unitary in character and in a form permitting advantageous connection with associated members of the car framing. In this figure the framing posts 333 are shown to be continuous and interlocked with the belt rail assembly as in the constructions shown in Figures 4 and 5 and before referred to, though obviously the posts 60 may terminate at the belt rail as in common practice, and the intermediate sill member 329, made sectional in the present form, may be extended continuously between the inner and outer rails without interruption.

The intermediate member is formed on its outer and inner faces respectively with grooves 330 and 331 having each a plurality of shoulders 332 at the upper and lower margins adapted to receive between them corresponding shoulders 334 on complementary rib portions 335 and 336 projecting respectively from contiguous faces of the outer and inner rail members 327 and 328. To insure complete interengagement of the parts, the rails and intermediate member are held together pref- 75

erably by rivets 331 extending through rib 335 and groove 330 at the outer side of the belt rail assembly and rivets 338 extending through rib 336 and groove 331 upon the inner side thereof, 5 so that the metal of the ribs will tend to fill respectively adjacent grooves under pressure of the riveting operation to effect positive interlocking of the several members and virtual integration of the assembly, whereby the rivets will be 10 relieved of shearing stresses to which they would otherwise be subjected.

Similar provision may be made for interlocking of other framing members of the car structure, notably the side plate assembly illustrated in Figure 5. As depicted in Figure 16, the web 161 of side plate longitudinal 122 is formed with groove 339 provided with marginal shoulders 340 and the web 165 of the side plate longitudinal 123 with rib 341 having shoulders 342 adapted to be received between and engage the corresponding shoulders 340 after the rib has been entered in the groove and secured in such interlocking relation by rivets 343 extending through the rib 341 and groove 339. Thus assembled, relative displacement of the side plate longitudinals and resultant distortion of the roof plates 24 and car lines 59 is prevented, the whole structure at the roof line appreciably rigidified, and the rivets connecting the longitudinals relieved of shearing 25 stresses normally imposed by the weaving movements of the car framing and incident to joints depending on rivets alone to transmit the loads from one to another of the assembly members.

The car may be equipped with any approved 35 air conditioning system, not shown, for heating, cooling and circulating the air within the car. Fresh air may be supplied to the system through intakes 345, and openings 346 may be provided at the rear of the car further to ventilate the smoking compartment or lounge customarily located at that end. Exhaust ventilators 347 are provided at the front or vestibule end of the car shown for servicing toilet rooms arranged for coach occupants at that end of the car and other 40 exhaust ventilators 348 for toilet rooms intermediate the ends of the car for accommodation of passengers at the rear of the car. For buffet service requirements, a smoke jack 349 may be provided for the kitchen range, but the kitchen 45 itself may be ventilated by an exhaust fan serving a duct (not shown) leading to ventilators 348. The exhaust ventilators and air intakes may be of any approved design but are shown with slip-stream outlines to reduce air resistance and to 50 accord with the general streamline contour of the car body.

Reference has been made to the massing of metal in the compression members of the side wall girder elements 18 and 26 for the purpose of 55 localizing stresses of compression within the zone of such members. However, with respect to the post members 33, metal has been massed at one side of the neutral axis X-X centrally of the post longitudinally of the car, to balance the 60 metal in the section of the post upon the opposite side of the neutral axis, to compensate for the break in continuity of the metal in one side of the post or a change in the disposition of such metal. In the present embodiment, the flanges 43 of the 65 posts 33 have been made thicker than the side walls 37 and web 40 to compensate for the lack of metal in the space between the flanges 43 at the inner sides of the posts whereby the metal in the full post section will be balanced upon opposite 70 sides of the neutral axis midway between the in-

ner and outer sides of the posts to effect stability of the posts in the framing assembly.

Post stability results from the equable distribution of metal upon opposite sides of a neutral axis substantially midway between the inner and outer sides of the posts as here involved, and that principle will control whether the flanges 43 are thickened and inwardly directed as shown or the webs 40 thickened and the flanges 43 disposed outwardly and reduced to the thickness of the side 10 walls 37, to the end that whatever the contour of the post or disposition of the metal on one side of the neutral axis, the mass of metal upon the opposite side of the neutral axis will be substantially the same to fix the position of the neutral 15 axis midway between inner and outer sides of the post to insure complete stabilization of that member.

Posts 34 are virtually the same as the narrower posts 33 with the webs 40 of the latter divided to provide outer flanges 40^a for attachment to girder plates 18 and 26 and intermediate connecting wall plates 39, and also utilize the stabilization feature to the extent that the neutral axis thereof, parallel to the girder and wall plates mentioned, 25 will be in substantial alignment with that of the other posts, since the flanges 43 of the wider posts are likewise thickened to compensate in some measure the addition of the wall plate metal connecting outer flanges 40^a. The balance thus 30 effected in posts when framed into the longitudinal compression members of the side wall construction in substantially the plane of the neutral 35 axes of the belt rail and side plate assemblies, will aid materially to prevent bulging of the side 40 wall structure and distortion in the several members under thrust of impact and weaving loads.

In the same way, the principle governing the balancing of metal at opposite sides of the neutral 45 axis of a member of irregular shape and formed 40 for advantageous connection with associated members of the car structure, may be extended to the side sills 21 and side plate longitudinals 22 and 23 to permit the assembling therewith of transverse underframe members and roof car lines, respectively, and the posts, as hereinbefore described. In the present embodiment, the inwardly extending upper flanges 69 of the side sills are made heavier than the lower inwardly and outwardly projecting flanges 70 and 71 combined 50 in order to balance the sill metal about a neutral axis intersecting the sill web 68 substantially midway of the upper and lower faces of the sill.

The sills being formed by the extrusion process 55 may be shaped as required for connection with 60 or accommodation of any associated car part or fitting. As shown in Figures 4 and 6, the flanges 69 and 70 are adapted to receive between them the ends of the bolsters 86, floor beams 121, cross-bearers 83 and end sills 77, while the side plates, 65 preferably of extruded metal, may be shaped integrally to receive the upper ends of the posts of the side structure and ends of transverse roof members of the form shown or any other approved construction.

It will be noted that repeated reference has 70 been made to extruded members forming the stress elements of the car structure. By that designation it is intended herein to cover such members produced by the extrusion process 75 which involves the method of forcing plastic metal under high pressure through a die having an aperture of the contour desired for the member to be formed, and references herein to such members made of aluminum are intended to em- 75

brace within the scope of the appended claims extruded metal shapes of metal other than aluminum and suitable for use in the extrusion process. As first above stated, the members produced by the extrusion method are characterized by accurately gaged definition of contour free from irregularities and practicable for interlocking connection with other members having like characteristics, whereby the number of parts in the assemblies where used is substantially reduced, with resultant saving in weight and cost of fabrication.

Conceivably, members having the requisite delineation of contour adapted for interlocking connection and produced by methods other than the extrusion process if obtainable within tolerances permissible in the interlocking relation as herein contemplated, whether aluminum or other metal, may be substituted for the extruded sections, if preferred.

As previously pointed out, the massing of metal in the compression members of both the upper and lower girder elements of the car side framing assembly substantially increases the capacity of the girder plates to function as stress transmitting members of the structure by placing such plates in tension over the larger part of their respective areas. The arrangement not only effects considerable reduction in the weight of the material entering the framing structure of steel cars, but, as before stated, permits a practicable use of metal having a relatively low modulus of elasticity with a minimum of deflection in the completed car. Due to the material saving in weight of the car as a result of the system of framing employed, the number and/or size of the axles of the supporting trucks may be substantially reduced.

In Figure 7 is shown one of the strut members 34 of the underframe utilizing extruded metal top and bottom members 184 and intermediate connecting member 182 and illustrates the adaptability of extruded metal to various phases of car construction. Within the scope of the invention, it is contemplated to incorporate extruded metal parts in the fabrication of bolsters, crossbearers and center sills where feasible and in combination with rolled flat plate members or extruded or pressed as suggested by the intermediate connecting member 182 of the strut assembly.

What we claim is:—

1. In a railway car framing, a side wall structure including a girder having a relatively heavy top chord member, a relatively light bottom chord member, a plate uniting said members having the major part of its area in tension, a roof framing member complementing said top chord to form therewith a side plate longitudinal in the framing assembly and having spaced inner and outer flanges projecting upwardly from the margins of said plate, transversely extending framing members supported upon said plates with their ends between said flanges, and a roof plate connecting said transverse members and side plate.

2. In a railway car framing having side wall structures comprising upper and lower girder elements including heavy top chord members, lighter bottom chord members and connecting webs having the major portions of their areas in tension, an end framing structure comprising end plate and sill members extending transversely of the car and connecting said upper and lower girders respectively, an underframe including side sills for supporting the side struc-

tures and center sills secured to said end sill member and projecting therebeyond for supporting a vestibule platform, a vestibule end framing including a buffer end sill mounted upon said center sill, and roof framing members overhanging said platform connecting the side wall, vestibule, and end framing assemblies, said buffer end sill providing a housing for a buffing mechanism.

3. In a railway car framing side wall structure 10 a girder having a relatively heavy top chord member, a lighter bottom chord member, and a plate uniting said members having the major portion of its area in tension, said top chord member comprising a plurality of preformed longitudinally extending continuous members connected to provide a unitary stress member and having each of them depressed and relatively higher areas in their contiguous faces adapted each of said higher areas on one member to engage a correspondingly depressed portion in the face of the companion section.

4. In a railway car framing, a side wall structure comprising an upper girder and a relatively large lower girder having each a relatively heavy top chord member, a relatively light bottom chord member, and a plate uniting said members having the major portion of its area in tension, said lower girder top chord member comprising a plurality of preformed members connected to provide a unitary stress member and having each of them depressed and relatively higher areas in their contiguous faces adapted each of said higher areas on one member to engage a correspondingly depressed portion in the face of the companion section.

5. In a railway car framing, a side wall structure including a girder having a flanged top chord member with a web portion forming one or more depressions and relatively higher areas in its upper face, a relatively light bottom chord member, a plate uniting said members having the major part of its area in tension, a flanged longitudinal roof framing member having a web portion formed with one or more depressions and relatively higher areas in its lower face adapted each of said higher areas on one of said webbed members to engage a correspondingly depressed portion in the contiguous face of the top chord member and forming therewith the side plate longitudinal in the framing assembly, a roof plate secured to and extending upwardly and inwardly from said side plate, and means connecting said roof and side plates.

6. In a railway car framing, a side wall structure including a girder having a top chord member formed with one or more depressions and relatively higher areas in one of its faces, and a roof framing member having a portion formed with one or more depressions and relatively higher areas in one of its faces and connected with said top chord member to provide a unitary side plate longitudinal in the framing assembly, said roof and top chord members being arranged with the higher areas on one member engaging a correspondingly depressed portion in the contiguous face of the companion section.

7. In a railway car framing, a side wall structure including a girder having a top chord member formed with one or more depressions and relatively higher areas in one of its faces, and a roof framing member having a portion formed with one or more depressions and relatively higher areas in one of its faces and connected with said top chord member to provide a unitary side

- plate longitudinal in the framing assembly, said roof and top chord members being arranged with the higher areas on one member engaging a correspondingly depressed portion in the contiguous face of the companion section, and a roof plate connecting said members.
8. In a railway car framing, a side wall structure including a girder having a plurality of top chord members formed with one or more depressions and relatively higher areas on their inner faces, a continuous inner framing member connecting said top chord members to provide a unitary belt rail longitudinal in the framing assembly, and framing post members between said top chord members, said inner rail member being formed on one face with one or more depressions and relatively higher areas and arranged with its higher area engaging corresponding depressed areas on the top chord members and its depressed portion the high areas on contiguous faces of the top chord members between said posts.
9. A railway car framing structure including side wall girders having each a top chord formed of a plurality of preformed longitudinally extending continuous sections connected to provide a unitary member, said preformed members having each of them depressed and relatively higher areas in their contiguous faces adapted each of

said higher areas on one member to engage correspondingly depressed areas in the face of the companion section, a bottom chord, and a plate uniting said chords.

10. In a railway car framing structure, a side girder having a top chord comprising a plurality of preformed longitudinally extending continuous sections connected to provide a unitary member, said preformed members having each of them depressed and relatively higher areas in their contiguous faces adapted each of said higher areas on one member to engage correspondingly depressed areas in the face of the companion section and together constituting a side plate longitudinal in the framing assembly. 5

11. In a railway car framing structure, a side girder having a top chord member comprising a plurality of preformed longitudinally extending continuous sections connected to provide a unitary member, said preformed members having each of them depressed and relatively higher areas in their contiguous faces adapted each of said higher areas on one member to engage correspondingly depressed areas in the face of the companion section and together constituting a side plate longitudinal in the framing assembly. 10
